UNITED STATES PATENT OFFICE.

WILLIAM WALTER WILKINS, OF CHICAGO, ILLINOIS.

DESIGN FOR A HORN.

Application filed May 2, 1924. Serial No. 9,470. Term of patent 3½ years.

To all whom it may concern:

Be it known that I, WILLIAM WALTER WILKINS, a subject of the King of Great Britain, residing at Chicago, in the county of Cook and State of Illinois, have invented a new, original, and ornamental Design for Horn, of which the following is a specification, reference being had to the accompanying drawing, forming part thereof.

The figure is a perspective view of a horn, showing my new design.

I claim:

The ornamental design for a horn as shown.

WILLIAM WALTER WILKINS.
